FLARE STACK APPARATUS FOR BURNING WASTE GASES

Robert A. Verner, Linden, and John P. Longwell, Scotch Plains, N. J., assignors to Esso Research and Engineering Company, a corporation of Delaware

Application June 29, 1951, Serial No. 234,398

2 Claims. (Cl. 158—109)

The present invention relates to an improved apparatus for effecting substantially smokeless combustion of gaseous, combustible materials, and more particularly, gaseous hydrocarbon materials. The invention relates especially to a method and means for burning waste refinery gases by the use of flare stacks, and includes means for modifying conventional flare stack apparatus.

In many industrial operations, and particularly in the refining of petroleum oils, large volumes of combustible gaseous materials are produced which have no real economic value either as fuel or otherwise. In addition, in venting safety valves and other similar devices, the exhausted gases must be safely disposed of. The volume of such gases and their hazardous nature makes it impossible for them to be exhausted directly into the atmosphere. Normally, they are burned as discharged from exhaust or flare stacks at a considerable distance above the ground, although on occasion relatively low, large diameter flare structures may be employed.

In burning such gases in the conventional manner, difficulty is experienced in providing sufficient quantities of air to accomplish complete combustion at the stack discharge. As a result, large quantities of heavy, sooty smoke are produced to create undesirable atmospheric pollution in the vicinity of the operation. An additional objection to present burning methods and means is to be found in the luminosity of the flame produced. Primarily, this is due to the fact that the flame of the ordinary flare contains large quantities of incandescent carbon particles. These particles may form dense, sooty smoke upon cooling.

In the conventional operation, the gases are discharged from the open upper end of a flare stack without substantial premixing of air therewith and are ignited, as discharged, by a continuous pilot flame. Combustion of the gas thus takes place in air rather than as a combustible mixture of gas and air. The flame thus produced is known as a diffusion type flame. Although a portion of the gas may burn immediately, the oxygen deficiency induces carbon formation, and especially where olefinic materials are present. In addition, it has been found that the heat generated by combustion of a portion of the gas stream may cause cracking of the unburned portions to form additional olefinic and paraffinic materials and, under severe conditions, carbon and hydrogen. At the same time, some molecules may polymerize to form long chain hydrocarbons. The combustion or partial combustion of such compounds increases carbon formation particularly in the presence of hydrogen and a reducing atmosphere.

2

Various attempts have been made to overcome the defects of the conventional flare stack operation but without substantial success. These efforts have ranged from attempts to adapt the principles of Bunsen, and other similar gas burners, to flare stack operation, to those according to which the required combustion air is supplied directly by means of blowers, or otherwise induced dilution of the gas stream with air, prior to ignition.

The use of flare stacks operated in a fashion similar to a Bunsen type burner has been largely unsuccessful for the reason that such type of operation requires that the gas be supplied to the burner at a substantially constant rate and high flow velocity in order to prevent reverse flow of the combustible gas through the air induction inlets. Furthermore, as the gases to be burned are usually exhaust gases from process equipment which must be released without substantial back pressure, they are usually discharged at pressures close to atmospheric pressure, and it would be impractical and uneconomic to repressurize such gases once they had been released from the process pressures. Where air dilution or pre-mixing of the gas stream with a forced air supply has been attempted, it has been found that the volume of air required plus the volume of combustible gas to be burned would necessitate employment of flare stacks of excessively large diameter. For example, whereas a conduit six inches in diameter would be adequate as a flare stack according to conventional procedures, to obtain an optimum flame condition by dilution of the gas with air prior to discharge of the gas from the stack, in the burning of each 1000 cubic feet of gas, provision would have to be made for the stack to handle about 6000 cubic feet of air per minute in addition. With such volumes of air and gas, the stack would have to be about sixteen inches in diameter. Considering the large volumes of gas required to be disposed of, the size of the stacks needed would present a considerable problem, and the cost of construction, including means for providing such large quantities of air, would be excessive.

As compared with previous solutions for the problem involved, it is an object of the present invention to provide a means for substantially complete combustion of the gaseous waste materials without inspiration or forced feeding of the required combustion air through the burner means employed. It is also an object of the invention to provide for substantially complete combustion of these gaseous materials under circumstances in which the materials are burned by producing turbulent diffusion of combustion air into a stream of combustible gas discharged from a generally conventional flare stack structure, with the required air being derived directly from the surrounding atmosphere. It is also an object of the invention to prevent thermal cracking and polymerization reactions in a burning stream of gas, tending to form undesired combustion products. A further object of the invention is to provide simple and economical means for carrying out a method according to this invention, and which means may be readily adapted for use with existing flare stack structures for the purpose contemplated.

The invention and its objects may be more fully un-

derstood from the following description when read in conjunction with the accompanying drawings in which:

Fig. 1 is a diagrammatic view, partly in vertical section, of a typical flare stack installation according to the present invention;

Fig. 2 is an enlarged vertical section of the upper end of the stack illustrated in Fig. 1;

Fig. 3 is a similar view of an adapter as applied to an existing stack structure and suitable for conversion thereof for operation as now contemplated;

Fig. 4 is a similar view of a modified form of apparatus according to the present invention;

Fig. 5 is a horizontal section through the apparatus of Fig. 4, taken along the line V—V thereof.

Referring to the drawings in greater detail, the numeral 1 designates a typical flare stack structure. As shown in Fig. 1, the stack is mounted on a base portion 1a and has a discharge outlet end 1b, a conduit 2 opening into the lower end of the stack provides for the introduction of combustible waste gases. As shown, the conduit 2 communicates with a water seal drum 3 provided with an inlet conduit 4 which extends into the drum by extension 4a to open below the surface of a body of water 5 maintained in the drum as by means of water inlet line 5a. The line 5b provides for drainage of the drum. The inlet conduit 4 is connected to and communicates with a suitable source of exhaust gases which are to be disposed of by burning upon discharge from the stack 1. Suitable ignition and pilot flame means, not shown, are provided for initial and subsequent ignition of the gases issuing from the discharge end 1b of the flare stack.

In addition, and as shown in Fig. 1, a conduit means 6 provides for the injection of a stream of a vaporized or gaseous, substantially non-combustible, diluent material, such as steam, into the upper end of the flare stack 1. The conduit 6 enters the stack through a side wall thereof, and terminates therein in an injection end portion 7 disposed coaxially with the stack and opening upwardly toward the open end 1b thereof. The disposition of the injection end portion 7 within the stack end portion 1b is more clearly illustrated in the enlarged view provided by Fig. 2.

As shown in Fig. 2, the center line x—x of the stack 1 and end portion 1b is common to the injection end portion 7 of the conduit 6. The portion 7, while illustrated as a simple jet as provided by an open-end, pipe fitting or nipple, may be replaced by a constricted jet discharge nozzle element as desired. In any event, however, the outlet of the nipple or nozzle 7 should be located in vertically spaced relation to the open or outlet end of stack portion 1b so that with a substantially cone-shaped pattern imparted to a diluent fluid discharged from the nozzle 7, the surface thereof will be substantially coincident with a conical surface including a line y—y drawn through the peripheral edges of the nozzle 7 and the open end of the stack portion 1b. Furthermore, the location of the nozzle 7 should be such that under any given conditions of operation, a fluid material discharged from the nozzle 7 will be substantially completely mixed, with the gaseous material passing through the stack prior to discharge of the combined materials therefrom, while imparting gross turbulence to the combined stream of materials issuing from the stack, and with a minimum condensation effect where steam is the fluid material employed.

When a simple jet discharge element, such as the pipe nipple 7 illustrated, is employed, the location of the outlet thereof with respect to the outlet of the stack portion will be generally determinable as that level at which the inner peripheral edges of the discharge element outlet intersect the surface of an inverted right conical surface based on the inner peripheral edge of the stack portion 1b, and having an apex angle of about 32°. Expressed otherwise, this level will be that at which the line y—y drawn between said edges, and extended to intersect the center line x—x will form an angle of 16° C. with said center line. Specifically illustrating such disposition of the nozzle 7, in a

stack having an internal diameter of twenty inches, the outlet of a three inch pipe nipple discharge nozzle will be spaced from the outlet end of the stack by a distance of about twenty-eight inches. In another such installation, a simple jet nozzle consisting of a pipe nipple of one inch internal diameter was disposed within an eight inch stack spaced from the open end thereof by a distance of about twelve and one-tenth inches.

As illustrated in Fig. 1, the conduit 6 is provided with a trap 6a at the lower end of the vertical portion thereof, and also with a flow control valve 8; a valve by-pass line 9; and suitable by-pass valves 9a, 9b, and 9c. The flow control valve 8 may be operated by means of a flow controller instrument 10 connected to the conduit 4 and actuated by the registered flow of combustible gases therethrough.

The method and apparatus is equally suited for use in conjunction with existing flare stack structures, and in Fig. 3, a typical means for such modification is illustrated. In this drawing, the numeral 21 designates the upper end of an existing flare stack having an open discharge end provided with a collar portion 21a. An adapter element 22 forms an extension of the stack conduits. This adapter element is of the same inside diameter as the stack conduit for the greater portion of its length but is flared outwardly at its lower end, as at 22a, to accommodate the outside dimension of the stack, or the collar 21a. This enlarged portion of the adapter element is of sufficient length to accommodate an annular clamp member 23 and slotted portions 22b extended into the body of the enlarged portion longitudinally from the lower peripheral edge portion 22c. Pressure exerted by means of the clamp and clamp bolts 23a compresses the enlarged portion to engage the collar 21a or stack 21 and to establish the adapter in fixed relation thereto. The adapter element 22 is also provided with an injector means, including an exteriorly disposed section 26 adapted for connection to a conduit line such as the line 6 of Figs. 1 and 2, and an injection end portion 27 comparable in nature and disposition to the portion 7 of Figs. 1 and 2.

In operation of the apparatus described, combustible exhaust gases are exhausted by way of the flare stack 1 and ignited at the discharge end thereof. A substantially inert, fluid diluent material is supplied to the upper end 45 of the stack 1, as by means of the conduit 6, and discharged into the stack, by way of the nipple or jet nozzle member 7, in such fashion as to be thoroughly and substantially completely mixed with the gases passed through the stack at about the outlet therefrom. The velocity of 50 discharge from the nozzle 7 is also regulated to produce a high degree of turbulence in the combined stream of materials issuing from the stack, whereby such turbulence increases normal inspiration and diffusion of atmospheric air through the issuing stream. Turbulence in the stream 55 of combustible gases is further increased by rapid expansion of the gaseous diluent material upon ignition of the combustible gases with which combined. Normally the flow of diluent material through line 6 is controlled automatically by the valve 8 in proportion to the flow of combustible gas through line 4, but if necessary or desired, with valves 9a and 9c closed, the flow may be diverted through line 9 and controlled manually by means of valve 9b.

Although many types of diluent materials may be employed by discharge in the manner described, including air and even nitrogen, steam has been found to be exceptionally effective for the purpose contemplated. Satisfactory results were obtained when operating by the injection of steam using steam, at 110 pounds' gauge pressure, injected at rates of from about 0.2 to about 0.7 pound per pound of combustible material in the gas to be burned. Exhaust steam at lower pressures may also be employed with generally equivalent results. These results, classified by the character of the flame obtained, are listed in the 75 following tables:

5
TABLE I

Flame Condition	Gas			Steam, Lb./Hr.	Ratio		
	Total SCFH	Combustible			Lb. Steam Lb. Comb.	Average	
		SCFH	Lb./Hr.				
No Trailing Smoke	19,700	14,870	1,730	400	0.231	0.27	
	13,300	10,020	1,170	330	0.222		
	7,700	5,800	676	200	0.296

	11,700	8,940	485	390	0.805		

The same waste gas materials burned without steam injection produced a long trailing flame of intense luminosity, and large amounts of dense, sooty smoke.

The exhaust gases burned as recorded respectively in Tables I and II; each had a composition as indicated by the following analyses:

Component		Table Number	
		I	II
CO ₂	vol. percent	0.6	4.6
H ₂ S	do	4.0	2.3
O ₂	do	1.6	0.1
N ₂	do	22.4	11.0
CO	do	0.0	7.9
H ₂	do	0.8	27.0
C ₁	do	9.2	6.2
C ₂ =	do	0.8	10.8
C ₂	do	9.4	22.8
C ₃ =	do	3.3	4.3
C ₃	do	22.0	1.5
iC ₄	do	8.3	1
nC ₄	do	11.8	0.4
C ₄	do	2.2	1
iC ₅	do	2.3	0.2
nC ₅	do	1.1	0.2
C ₅	do	0.1	0.3
C ₆	do	0.1	0.6
Combustible	do	75.4	76.4
Unsat. Vol. percent of Comb.		8.5	20.8
Avg. Mol. Wt. of Comb.		44.1	20.7
Sp. Gr. Comb.		1.52	0.71
Sp. Gr. Total Gas		1.37	0.72

As indicated in the test reported according to Table II, the combustible gas contained a considerably larger volume percent of unsaturated material.

Atmospheric conditions which existed at the time the results according to Tables I and II were obtained, are indicated by the following table:

Atmospheric conditions		Table Number
Condition		
Temperature	°F.	78
Pressure	in. Hg.	30.3
Wind Velocity	M. P. H.	10

By comparison of the results reported by Tables I and II, and in conjunction with the analyses of the gases

burned, it is evident that the quantity of steam required to obtain a flame of any desired character, will vary with both the quantity and quality of the gas being burned. With particular reference to the relative degree of unsaturation it is indicated that steam requirements increase in direct relation to the degree of unsaturation.

Operations according to the present invention are indicated to be effective in several ways to suppress the formation of carbon and other undesired products of ordinary combustion. First by mixing an inert diluent, and steam particularly, with the combustible gas prior to ignition, the molecules of the combustible material are separated by the diluent material. Secondly, the presence of the diluent, and particularly steam, tends to reduce the combustion temperature. Where hydrocarbon gases are burned, separation of the molecules tends to minimize polymerization with its consequence of increased carbon formation. At the same time, reduction of combustion rate and temperature tend to reduce the effects of cracking unburned gases to produce undesired olefinic and paraffinic materials. Further, the reduction of combustion temperatures, and the substantial elimination of incandescence increases the normal life of the flare stack at the discharge end. Also when steam is employed as a diluent material, a water gas reaction is promoted, wherein the gases to be consumed are carbon monoxide and hydrogen, producing a non-luminous, substantially sootless flame in contrast to that of burning hydrocarbons.

In Figs. 4 and 5, the concept of this invention is shown as applied to an apparatus for burning combustible exhaust gases which apparatus is known as a "ground flare." The flare as represented in the drawing is composed of three concentric, radially spaced cylindrical elements 31, 32 and 33. In a typical structure, the outermost element 31 may be about thirty feet in height, and have an inside diameter of about fourteen feet; the innermost element 33 a height of about four feet and an inside diameter of about thirty inches; and the intermediate element 32 a height of about twelve feet and an inside diameter of about six feet. Normally, each of the elements 31, 32 and 33 will be constructed of reinforced fire brick, the outermost element 31 being constructed so as to provide a substantially annular flue-like space 31a between inner and outer surface portions of the wall thereof. Each of the elements 31, 32 and 33 is provided with a plurality of open ports 31b, 32b, and 33b adjacent the bottom thereof, permitting entrance

of atmospheric air into the interior of the respective elements under the influence of the thermal draft created by burning of exhaust gases. The upper end of element 33 is preferably chamfered inwardly as shown at 33a, with a plurality of cooling passageways or ports 33c opening angularly from the outer wall surface through the chamfer surface.

The innermost element 33 serves as the discharge outlet for the combustible exhaust gases to be burned. These gases are supplied thereto by means of an exhaust gas conduit 34 extended through the respective concentric elements and having an outlet end 34a opening into the bottom portion of the cylindrical element 33. As shown, the outlet 34a is provided with a helically vanned interior surface designed to impart some degree of swirling motion to the exhaust gases as discharged therefrom. Means for ignition of the combustible gases discharged from the upper end of the element 33 is provided as by a pilot gas flame from the discharge end of a supply conduit 35. Any suitable means, not shown, may be provided for ignition and maintenance of the pilot flame as desired.

According to the present invention, the center element 33 of the ground flare structure as set forth above is additionally provided with means for injecting a stream of vaporous fluid diluent material into the stream of combustible exhaust gas discharged from the element 33, immediately prior to discharge into the surrounding atmosphere, at an initial velocity greater than that of the stream, so as to dilute the gaseous stream and induce gross turbulence therein substantially at and beyond the point of discharge from the element, the exhausted gaseous material then being burned in the presence of the diluent. The injection means, as shown, includes a supply conduit 36 communicating at one end with a source of a vaporous diluent material, such as steam, and at the other end extended through the sidewalls of elements 31, 32 and 33, and concentrically upward within the latter into vertically spaced relation to the upper end thereof. The conduit 36 terminates within the element 33 in a discharge nozzle portion 37, in a manner similar to that illustrated and described with reference to Figs. 1 to 3, inclusive, and for the same purpose. The outlet of nozzle 37 also is spaced from the upper end of the element 33 by a distance such that the inner peripheral edges of the nozzle outlet intersect the surface of an inverted right conical surface based on the lower peripheral edge of the chamfered portion 33a.

As compared with the apparatus illustrated in Figs. 1 to 3, inclusive, where the combustible gases are discharged directly into the atmosphere, and combustion air derived therefrom, entirely by the inspirating effect of turbulence in the burning gases as induced by injection of the diluent material, and the expansion thereof by the heat of combustion, in the apparatus according to Figs. 4 and 5, combustion is initiated in a confined combustion zone as provided by the intermediate and outermost elements 32 and 31. Combustion air, while inspirated and diffused into the burning stream of gases in the same fashion as in the apparatus according to Figs. 1 to 3, inclusive, primarily is derived by thermal draft induction through the passageways or ports 31b, 32b, and 33b. The flow of air through ports 33b is partly due to the inspirating effect of the jet of diluent material discharged from the jet discharge nozzle 37. Operation of the apparatus according to Figs. 4 and 5, is generally comparable to the operation of the apparatus illustrated by Figs. 1 to 3, inclusive, and as described with reference thereto.

What is claimed is:

1. In a flare stack structure, including a vertically elongated flare stack conduit, means forming an inlet for

combustible gaseous materials opening into said stack conduit adjacent the lower end thereof, conduit means connecting said inlet means to a source of said combustible gaseous materials, and wherein said conduit stack terminates at the upper end thereof in a discharge end opening into substantially unrestricted communication with the atmosphere surrounding the stack and is adapted to discharge a stream of gaseous material into said atmosphere, a means for inducing gross turbulence in said stream of gaseous materials and for diluting said stream with steam immediately before and after discharge thereof into the atmosphere, comprising a steam supply conduit extended upwardly into said stack conduit, a discharge nozzle at the terminal end of said supply conduit within the discharge end of said stack conduit disposed in substantially concentric relation to said stack conduit, said nozzle having a discharge outlet of a radius substantially equal to from about one-seventh to about one-eighth the radius of said flare stack conduit, said nozzle opening toward the discharge end of said stack conduit and disposed in vertically spaced relation thereto by a distance substantially equal to the product of the natural cotangent of an angle of 16° multiplied by the difference between the radius of said stack and the radius of said nozzle discharge outlet, and wherein said nozzle is adapted to provide a steam discharge pattern having a substantially inverted conical contour with an apex angle of about 32°.

2. An apparatus according to claim 1 wherein said flare stack conduit comprises a lower conduit section having an upper end, an annular collar secured to said upper end circumferentially thereof, and an upper conduit section constituting said stack conduit discharge end, said upper conduit-section including a body portion, having an upper end and a lower end, said body portion having a radius between said ends substantially equal to the radius of said lower conduit section, and a radially enlarged portion extending from and beyond the lower end of said body portion, said enlarged portion being adapted to receive the upper end of said lower conduit section telescopically, and frictionally to engage said collar thereon, said enlarged portion being provided with a series of vertical slots extending upwardly through the lower peripheral edge thereof and disposed in parallel spaced relation one to another circumferentially of said enlarged portion, and an annular clamp encircling the slotted end of said enlarged portion, said clamp adapted to compress said slotted end of the enlarged portion into rigid engagement with said collar and the upper end of said lower conduit section, and wherein said steam discharge nozzle is disposed concentrically of said upper conduit section body portion.
